UNITED STATES PATENT OFFICE

1,969,673

BOX FOR COSMETICS AND THE LIKE

Ferrest G. Purinton, Waterbury, Conn., assignor
to The Patent Button Company, Waterbury,
Conn., a corporation of Connecticut

Application May 5, 1932, Serial No. 609,381

1 Claim. (Cl. 229—3.5)

This invention relates to improvements in receptacles and particularly boxes which are used as containers for face powder, other cosmetics, and the like, and the object of the invention is to provide a receptacle or box of this character which can be economically constructed and which will simulate the appearance of relatively thick metal.

Boxes of this character, and particularly the covers of such boxes, have heretofore been constructed by drawing or stamping a sheet of brass, or other metal, to the desired shape and form, the cover being adapted to fit the box or container for the material, with suitable ornamentation applied to the top of the cover by engraving, or by dies, when such covers are stamped.

One of the objects of the invention is to provide a box comprising a cover and/or a base formed of relatively thin sheet metal in which the vertical walls of the cover and/or the base, and preferably the top and bottom of the cover and base, are respectively re-enforced by walls of fibrous material permanently secured thereto to provide a rigid construction of substantially the same durability as a receptacle or cover wholly formed of metal.

A further object of the invention is to provide a box of this character in which the vertical walls of the receptacle and/or the flange of the cover will present a relatively thick and nicely rounded edge more pleasant to the touch than the sharp metal edges of the walls of usual receptacles and flanges of the covers therefor.

A further object of the invention is to provide a box cover of the character specified which is ornamented by suitable pigmented coatings so interrupted as to display portions of the metal which, with the coating, or coatings, employed, will present a pleasing design.

These and other objects and features of the invention will more fully appear from the following description and the accompanying drawings and will be particularly pointed out in the claim.

Illustrative embodiments of the invention are shown in the accompanying drawings, in which,

Fig. 1 is a perspective view of a box having a cover embodying the invention;

Fig. 2 is a vertical sectional view of the casing of the top, of fibrous material, the thickness of thereof being exaggerated;

Fig. 3 is a vertical sectional view of the shell which tightly fits upon the casing illustrated in Fig. 2, the thickness being greatly exaggerated as the shell may be made of a thickness of .010";

Fig. 4 is a vertical sectional view of the assem-

bled top, the thickness of the walls being considerably exaggerated. Coats of lacquer, or other suitable material, are illustrated in Figs. 3 and 4 in greatly exaggerated proportion;

Fig. 5 is a vertical sectional view of a box embodying the invention, in which both the cover and the base are formed of complementary integral cup-shaped members of fibrous material, each closely enclosed in a shell of thin sheet metal, with an inner wall of fibrous material fitting within the vertical wall of the base and extending therefrom and adapted to be telescopically engaged by the flange upon the cover;

Fig. 6 is a vertical sectional view of a construction similar to that shown in Fig. 5, in which the walls of fibrous material are employed only to re-enforce the vertical wall of the base and the flange of the cover;

Fig. 7 is a vertical sectional view of a box embodying the invention in which the base and walls of the receptacle are formed of fibrous material, with the base having a flange or bead extending beyond the periphery of the wall, and in which the cover comprises a top, and a vertical wall adapted telescopically to fit the wall of the receptacle, both formed of fibrous material, with a thin sheet-metal shell enclosing the top and flange of the base and turned over the edge of the flange;

Fig. 8 is a vertical sectional view of a box embodying the invention in which the metal shell for the receptacle and/or the cover is so formed as to present a bead projecting from the margin of the top and/or the bottom;

Fig. 9 is a vertical sectional view of a box in which the bottom of the receptacle is provided with a projecting flange, with a thin sheet metal shell enclosing the bottom, the projecting flange and the vertical wall of the shell, and in which the re-enforcing fibrous wall of the cover is enclosed in a thin sheet metal shell and forms the top thereof, the shell being turned around the other edge of the wall to present a rounded edge; and,

Fig. 10 shows a cover having a top of fibrous material and a vertical flange of fibrous material of smaller diameter than the top, with a shell of thin sheet metal enclosing the top and flange, and bent around the edge thereof.

The various embodiments of the invention illustrated herein comprise in common a receptacle and/or a cover therefor formed of cup-shaped sheet metal, with vertical walls of fibrous material within the vertical portions of the shell,

certain of the forms illustrated being also provided with re-enforcing walls of fibrous material for the bottom or base of the receptacle and the top of the cover.

5 The construction illustrated in Figs. 1 to 4 inclusive comprises a receptacle and a cover therefor embodying the invention and provided with interrupted pigmented coatings displaying portions of the metal shell therebetween to produce an ornamental design.

10 The embodiments of the invention are illustrated herein as a cylindrical box, but it will be understood that the box may be of any other form, such as hexagonal, octagonal, rectangular, or elliptical, with a cover complementary thereto.

15 As illustrated in Figs. 1 to 4, the box or receptacle comprises a bottom 1 with a continuous wall 2 extending vertically upwardly therefrom to any desired height. The cover comprises an inner casing having a top 3 which is shown in the present embodiment as of circular form, and a cylindrical flange 4 extending vertically downwardly therefrom and adapted to slidably fit over the vertical wall 2 of the box or container.

20 The casing is made of non-metallic preferably fibrous material, such as paper stock, which may be made in cup-shaped form in any desired manner.

25 An integral self-sustaining shell of thin sheet metal having a top 5 and a downwardly extending flange 6 is constructed to fit closely upon the top 3 and flange 4 of the casing and is permanently secured thereto. It desirably extends sufficiently below the lower end to permit it to be turned over the lower edge of the flange 4 to present a protecting bead 7 having an edge somewhat thicker than the edge of the casing, and also to provide a nicely rounded and smooth edge which is more pleasing to the touch than the sharp metallic edge which otherwise would be presented by the thin metal shell, or which is found on usual metallic covers for boxes of this type.

30 The metal shell desirably is of zinc which, when burnished and lacquered, presents an appearance of silver. Zinc, by reason of its ductility, is especially adapted to the purpose herein described, although it will be understood that other suitable sheet metal may be similarly employed. Desirably the flange of the cover is of a width at least as great as the height of the flange of the box, so that the wall of the box is completely enclosed.

35 The box cover thus formed may be burnished to present a highly polished metal surface, but desirably is ornamented by a pigmented coating or coatings, preferably of lacquer, applied thereto in such a manner that portions of the metal will be exposed to form parts of the design.

40 In applying the coating, the box covers may be mounted respectively upon spindles carried by an endless chain which is so actuated as to present the box covers at different spraying stations, for example, one for applying a sealing coat of lacquer, another for applying a band or bands of lacquer around the outside, and others for applying a coating to the top of the box.

45 Suitable stencils may be applied to the boxes in advance of the several stations at which the colored lacquer is sprayed upon them and removed and replaced by others to enable different colors to be properly applied. The endless chain may desirably extend through a suitable heating chamber or chambers to complete the drying of

the coating, and the boxes may be repeatedly presented at the several stations in order that a desired number of coatings may be applied.

50 The stencils desirably are constructed to cover portions of the metallic shell so that after the coating of the boxes is completed and the stencils removed, the design will present areas of metal so that the box cover will simulate an ornamented metal cover.

55 As illustrated in Figs. 1, 3, and 4, herein, the top of the box is coated to present a circular field 8 of cream with a conventional ornamentation 9 of black thereupon, and a narrow ring of black 10 surrounding the field. The flange is provided with a band of black 11 which is somewhat narrower than the width thereof. The lower edge of the band terminates in a line 12 spaced apart from the edge 13 of the cover, thereby presenting a metal band 14 at the bottom of the cover. The line of the upper edge 15 of the black band is located at a short distance below the plane of the top 5 and presents a rounded metal annulus 16 surrounding the field and its encircling black band 10. Such metallic or silver bands greatly enhance the beauty of the design. Obviously, other designs may be employed, or the box uniformly coated.

60 In Figs. 5 to 10 inclusive different forms of boxes of the type above described are shown.

65 In Fig. 5 the receptacle comprises an integral cup-shaped container of fibrous material having a base 17 and a vertical wall 18 integral therewith, with a shell 19 of thin metal closely fitting the bottom and wall 18, with its edge portion 20 turned over the upper edge of the wall 18. A supplemental continuous wall 21 fits within the wall 18 and is permanently secured thereto and extends a desirable distance beyond the upper edge of the wall 18.

70 The cover comprises a cup-shaped casing of fibrous material having a top 22, a flange 23 integral therewith, with a thin metal shell 24 tightly fitting the cup-shaped casing and having its edge portion 25 bent around the lower edge of the flange 23. The cover is adapted slidably to fit upon the supplemental wall 21 of the base, so that the edges of the cover and wall of the base, when placed in abutting relation, will be substantially continuous.

75 Fig. 6 illustrates a construction in which the base comprises only a rigid vertical wall 26 of fibrous material with a shell 27 fitting over the wall providing a base or closure for the lower end of the receptacle and having its edge portion 28 turned over the upper edge of the wall 26. The cover likewise is provided only with a continuous vertical member or flange 29 of fibrous material enclosed in a thin sheet metal shell 30, the lower edge of the shell 31 being turned over the lower edge of the cover. In this construction, as in that shown in Fig. 5, a supplemental wall 32 fits within the wall 26, is secured thereto, and extends upwardly therebeyond to fit tele-

80 scopically within the flange of the cover.

85 In the construction shown in Fig. 7, the receptacle comprises a base 33 with walls 34 extending upwardly therefrom and preferably formed integral therewith. The base extends beyond the periphery of the wall 34 to present a flange 35. The cover, as illustrated in this construction, comprises a top 36 of fibrous material and a downwardly extending wall or flange 37 which may be made separate therefrom. A metallic shell 38 encloses the top 36 and flange 37 and is turned over the lower edge of the flange 37.

90 95 100 105 110 115 120 125 130 135 140 145 150

Fig. 8 shows a construction comprising a receptacle having a base 39 with a vertical wall 40 extending upwardly therefrom and a shell 41 enclosing said base and wall, but bent to form a bead or extension 42 simulating a flange extending beyond the periphery of the base. The upper edge 43 of the base is turned over the upper edge of the wall 40. A supplemental wall 44 fits within the wall 40 and extends above the upper edge thereof telescopically to engage the top. The top is of a construction similar to the bottom with the metal of the shell formed to present a bead or flange 45 extending around the top.

In the construction shown in Fig. 9 the base 46 extends beyond the periphery of the vertical wall 47 to provide an annular flange 48. A shell 49 of thin sheet metal is formed to fit and enclose the bottom, its projecting flange, and the vertical wall 47, and is turned over the upper edge of the wall.

In this construction the top comprises a cup-shaped shell 50 which extends beyond the sides of the re-enforcing members 51 of fibrous material to form an annular bead 52. The lower edge of the shell is bent around the edge of the re-enforcing member 51.

Fig. 10 illustrates a cover comprising a casing

having a top 53 and a re-enforcing vertical wall 54 located at a sufficient distance from the periphery of the cover to provide a projecting flange 55. The sheet metal shell 56 closely fits the top of the cover and extends over the flange 55 and encloses the vertical wall 54 with the edges of the shell bent over the edge of the vertical wall 54, thus presenting a flanged cover simulating a complete metal cover, but presenting a nicely rounded edge which is pleasing to the touch.

It will be understood that the particular embodiments of the invention shown and described herein are of an illustrative character and are not restrictive, and that various changes in form and construction may be made within the spirit and scope of the following claim.

Having thus described the invention, what is claimed as new, and desired to be secured by Letters Patent, is:

A receptacle member comprising an integral self-sustaining shell of thin ductile sheet metal having a base and a peripheral flange extending vertically therefrom, and a reenforcing wall of sheet material fitting within said peripheral flange and secured thereto by the turned edge 100 of said sheet metal flange.
